UNITED STATES PATENT OFFICE.

EDWARD M. SMITH AND MABEL E. SMITH, OF MILFORD, CONNECTICUT.

BASE-BALL GAME.

1,318,615.

Specification of Letters Patent. Patented Oct. 14, 1919.

Application filed April 6, 1917. Serial No. 160,272.

To all whom it may concern:

Be it known that we, EDWARD M. SMITH and MABEL E. SMITH, citizens of the United States, residing at Milford, in the county 5 of New Haven and State of Connecticut, have invented certain new and useful Improvements in Base-Ball Games, of which the following is a specification.

This invention relates to certain new and 10 useful improvements in games and has for its primary object, the provision of a baseball game which will be instructive as well as interesting and in which a small number of parts may be employed.

15 Another object of the invention resides in the provision of a game of the above stated character in which a spherical member representing a baseball may be employed to travel around a groove or runway in the 20 game board and opposite which groove or runway are located a number of squares having marked therein the various plays which may occur in a regular baseball game, the spherical member stopping opposite the 25 different squares to indicate the next play in this game.

A further object of the invention resides 30 in the provision of a baseball game in which the board may be marked in such manner as to represent a baseball diamond upon which the men representing the players of each side or team may be located, while the groove or runway for the spherical member surrounds this portion of the board and the 35 different plays are marked upon the outer edge of the groove or runway.

A further object of the invention resides 40 in the provision of a baseball game of the above stated character in which the board will be provided with suitable openings or 45 sockets to receive reduced ends of the members representing the different players, so that these members or game pieces may be properly positioned at all stages of the same.

A still further object of the invention resides in the provision of a baseball game of the character stated, in which the game board will be constructed in such manner 50 that a record of the "balls", "strikes", "innings", et cetera may be indicated on the board, without the necessity of employing extra means for keeping this record.

Still another object of the invention resides 55 in the provision of a baseball game of the character stated, in which the game

board will be constructed in such a manner and the words indicating the different plays arranged in such manner in the squares surrounding the groove or runway for the 60 spherical member, that a possible play will be indicated whenever the spherical member travels around the groove or runway, regardless of the position in which the spherical member stops within said groove 65 or runway.

With the above objects in view and others which may appear as the description proceeds, the invention consists in the novel combination and arrangement of coöperating 70 elements as hereinafter more specifically set forth, shown in the accompanying drawings and pointed out in the appended claim.

In the accompanying drawings forming a part of this application, and in which 75 similar reference characters designate corresponding parts throughout the several views,

Figure 1 is a plan view of the game board with the spherical member resting in 80 the runway,

Fig. 2 is a transverse section, substantially on the plane of line II—II of Fig. 1, looking in the direction indicated by the arrows,

Fig. 3 is a detail section on the plane of 85 line III—III of Fig. 1, and

Fig. 4 is a detail sectional view on the plane of line IV—IV of Fig. 1, showing a player or game piece in position.

Referring more in detail to the drawings, 90 1 designates the board which is preferably of circular form and which is provided in its upper face with a continuous groove or runway 2 for the spherical member 3. This 95 spherical member 3 is marked as a baseball but is preferably solid and of sufficient weight to eliminate danger of the spherical member being forced over the edges of the runway when traveling in the same. In 100 fact a spherical member similar to a billiard ball should be employed.

The central portion of the board is marked off to represent a baseball diamond and suitable openings or sockets 4 are provided in the board at the different bases and home plate and other proper positions to receive reduced ends 5 of the pieces 6 representing the different players on the two sides or teams. It will be understood that 105 110 openings or sockets 4 are also provided in the outer portion of the board in order that

game pieces representing the fielders may be supported in proper position.

The outer portion of the board 1, surrounding the groove or runway 2, is divided 5 into squares 7 having marked therein all of the different plays which may occur in a regular baseball game, one or more of the plays being marked in each square. In the present case, I have shown 35 squares as 10 indicated by the numbers surrounding the board with the plays marked therein but it will be understood that any suitable number may be provided.

In order to keep a record of the number 15 of innings and runs for each side, I have provided rows of openings or sockets 8 within the diamond and between the home plate and the first and third bases. These openings or sockets 8 may receive suitable 20 counting pegs 9 as shown in Fig. 3 of the drawings. In order to keep track of the "strikes", "balls" and "outs", I have arranged pointers 10, preferably outside of the running lines between the home plate and the 25 first and third bases, as shown in Fig. 1 of the drawings. These pointers 10 may be turned upon their pivots 11 to proper position over the numbers 12 arranged around the same to indicate "strikes", "balls" and 30 "outs" respectively, a complete set of pointers 10 being provided for each side or team.

As means for supporting the game board in a horizontal position upon its support 35 and always keeping the board level, so that the spherical member 3 may properly travel within the groove or runway 2, I have provided the supporting screws 13 which are threaded through the board, preferably the 40 outer portion of the same, and which rest upon the support with the game board 1 spaced above the latter. These adjusting screws have suitable heads 14, by means of 45 which they may be readily adjusted to raise or lower the sides of the board, as occasion may require.

In playing this game, the game pieces representing the players of one side or one 50 team are placed in the proper positions upon the board and then the game pieces representing the players of the other side or other team are placed in position at the point marked for the batter in consecutive 55 order, the spherical member 3 being rolled around the board to indicate the "strikes", "balls", "outs" and "plays" of the game, the "strikes", "balls", "outs" and "plays" being indicated by the position at which the spherical member 3 stops in the runway 2. This 60 is continued until three men of the side are

out and thereby completing one-half an inning, as in the regular baseball game. The men are then changed to give the other side or team a chance at the bat and complete the inning. The game is continued in 65 this manner until the proper number of innings have been played and, of course, the side or team having the greatest number of runs to its credit is declared the winning side or team. Any number of parties may 70 be represented on each side or team and the game will be found to be very instructive in the game of baseball as well as interesting and at times, even exciting, as very few runs are made by either side, on account of the 75 arrangement of the different plays in the square 7 around the runway 2. It is to be understood that every possible play in a regular baseball game should be represented in at least one of the squares 7 and should 80 be the spherical member 3 stop opposite one of the lines dividing two of the squares, a foul strike should be called on the batter.

While the preferred embodiment of the invention has been shown and described, it 85 will be understood that minor changes in the details of construction and arrangement of parts may be resorted to within the scope of the appended claims without departing from the spirit of the invention.

What we claim is:—

Game apparatus for playing baseball, comprising a circular board having a circular runway near its outer edge and having a marginal portion exterior to said runway 95 divided into spaces which bear directive matter corresponding with the possible plays, and having the center portion within the runway representing a diamond-shaped field including the bases, home plate and 100 pitcher's box, and having sockets for the infielders, there being sockets in the marginal portion for the out-fielders, and said board having two sets of sockets for the game pieces of the two teams and pointers 105 for the plays such as "balls", "strikes" and "outs", game pieces insertable in the sockets, and a ball freely movable in the circular runway and coöperating with the directive matter bordering thereon to indicate the 110 play and the position of the game pieces in play.

In testimony whereof we affix our signatures in presence of two witnesses.

EDWARD M. SMITH.
MABEL E. SMITH.
